US00D931284S

(12) **United States Design Patent** (10) Patent No.: **US D931,284 S**
Murase et al. (45) Date of Patent: ** Sep. 21, 2021

(54) **SCANNER**

(71) Applicant: **CANON DENSHI KABUSHIKI KAISHA**, Saitama (JP)

(72) Inventors: **Asako Murase**, Yokohama (JP); **Satoshi Shinata**, Yokohama (JP)

(73) Assignee: **Canon Denshi Kabushiki Kaisha**, Saitama (JP)

(**) Term: **15 Years**

(21) Appl. No.: **29/703,024**

(22) Filed: **Aug. 23, 2019**

(30) **Foreign Application Priority Data**

Feb. 27, 2019 (JP) 2019-004038

(51) **LOC (13) Cl.** **14-02**

(52) **U.S. Cl.**

USPC **D14/422**

(58) **Field of Classification Search**

(57) **CLAIM**

The ornamental design for a scanner, as shown and described.

DESCRIPTION

FIG. 1 is a front, top perspective view of a scanner in accordance with the present design;

FIG. 2 is a front view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.

1 Claim, 7 Drawing Sheets
